SHOESTRING KNOT RETAINER

William F. Getgey, Cincinnati, Ohio, assignor to Price-
Getgey Company, Cincinnati, Ohio, a corporation of
Ohio

Filed Nov. 14, 1966, Ser. No. 4,659

Term of patent 14 years

(Cl. D2—314)

Fig. 1**Fig. 2****Fig. 6****Fig. 7****Fig. 3****Fig. 4****Fig. 5****Fig. 6**

FIGURE 1 is a perspective view of a shoestring knot retainer showing my new design in an opened position, the broken line partial showing of a shoe and shoe strings being for purposes of illustration;

FIGURE 2 is a perspective view thereof showing the design in a closed position;

FIGURE 3 is a top plan view of the shoestring knot retainer;

FIGURE 4 is a bottom plan view;

FIGURE 5 is a front elevational view;

FIGURE 6 is a rear elevational view; and

FIGURE 7 is a side elevational view.

I claim:

The ornamental design for a shoestring knot retainer, as shown and described.
